UNITED STATES PATENT OFFICE

108,487

DESIGN FOR A SAVINGS BANK

Jerome B. Aronson, Chicago, Ill.

Application December 23, 1937, Serial No. 73,833

Term of patent 7 years

To all whom it may concern:

Be it known that I, Jerome B. Aronson, a citizen of the United States, residing at 560 West Lake Street, in the county of Cook and State of Illinois, have invented a new, original, and ornamental Design for a Savings Bank, of which the following is a specification, reference being had to the accompanying drawing, forming part thereof, in which:

Fig. 1 is a view in perspective of a savings bank embodying my design;

Fig. 2 is a top plan view of the savings bank. The printed matter "Jan. 10" on the side of Fig. 1 is merely illustrative of the use to which the openings are put.

I claim:
The ornamental design for a savings bank, as shown and described.

JEROME B. ARONSON.
